IRONING BOARD ATTACHMENT

Beatrice Hedges, Faribault, Minn.

Application February 25, 1949, Serial No. 78,396

3 Claims. (Cl. 38—106)

1

My invention relates to ironing boards and, more specifically, is in the nature of an attachment therefor.

The primary object of my invention is the provision of an attachment for ironing boards in the nature of an adjustable supporting means adjacent the side edges thereof which may be progressively extended in an outward and upward direction, when and as desired, to support the ironed portions of lengthy articles such as curtains, sheets, and the like.

I have found that, as the supplemental supporting bars are spaced from their normal positions adjacent the side of the board, it is highly desirable to progressively elevate them as they are moved outwardly. Therefore, it is a specific object of my invention to provide means in the nature of supporting bars which are so secured to the under portion of the ironing board that, when they are moved outwardly with respect to the side edges of the board, they will automatically be moved upwardly in an arcuate path.

Another provision of my invention is the provision of a device which, under the action of gravity, will lock itself against accidental removal in a desired set position without the use of clamping screws or the like.

A still further object of my invention is the provision of means for accomplishment of the above objects, which is inexpensive to produce, easy to secure to and remove from an ironing board, rugged in construction, and durable in use.

Other highly important objects and advantages of my invention will become apparent from the following detailed specification, appended claims, and attached drawings.

Referring to the drawings, in which like characters indicate like parts throughout the several views:

Fig. 1 is a perspective view of an ironing board with my novel device attached thereto;

Fig. 2 is an enlarged transverse section, taken on the line 2—2 of Fig. 1;

Fig. 3 is a view corresponding to Fig. 2, but showing a different position of some of the parts;

Fig. 4 is an enlarged transverse section, taken on the line 4—4 of Fig. 1;

Fig. 5 is a view, partly in section and partly in bottom plan, on an enlarged scale, as seen from the line 5—5 of Fig. 1, some parts being broken away; and

Fig. 6 is a still further enlarged sectional detail, taken substantially on the line 6—6 of Fig. 2.

Referring with greater detail to the drawings,

an ironing table is shown comprising a table top 1, rear supporting legs 2, front supporting legs 3, and braces 4. Legs 2 have their upper ends pivoted to brackets 5, as indicated at 6, the brackets 5 being rigidly secured to the under side of the board 1. Braces 4 are pivoted at their rear ends to the intermediate portions of rear legs 2 by rivets or the like 7 and have their front end portions connected by a relatively short cross member 8. The extreme front ends of braces 4 have abutting engagement with the under side of board 1 and the adjacent side of a stop member or cleat 9 rigidly secured to the under side of the ironing board 1. Legs 3 are secured together at their lower front ends by a rivet or the like 10 and, intermediate their ends, are pivotally secured one each of the intermediate portion of one of the brace members 4 by rivets or the like 11. The upper rear ends of legs 3 are joined by a cross member 12 and abut the under side of ironing board 1 and the adjacent side of a stop member or cleat 13 rigidly secured to the board 1. The ironing board structure immediately above-described, is of a type commonly used and the details thereof in themselves form no essential part of the invention herein claimed.

I provide a pair of brackets 14 and 15 attached to the under side of the board 1 adjacent the front and rear ends respectively thereof by screws or the like 16. Bracket 14 includes spaced mounting pads 17 and connecting tubular guides 18 and 19. As shown particularly in Fig. 4, guides 18 and 19 are open-ended and are longitudinally arcuate in form. Each of the guides 18 and 19 is provided with a longitudinally-extended slot 20, the purpose of which will hereinafter appear. Bracket 15 is similar to bracket 14 and comprises a pair of spaced mounting pads 21 and a pair of connecting tubular guides 22 and 23. Guides 22 and 23 are longitudinally arcuate, the arc thereof having the same radius as the arc of guides 18 and 19. It will be seen, by reference to Figs. 2-5 inclusive, that guide bracket 14 is of less length than guide bracket 15 to permit its being secured to the narrow tapered end of the ironing board 1. It is important to note that the intermediate portions of tubular guides 18 and 19 and tubular guides 22 and 23 are downwardly spaced from the ironing board 1 a like amount so that the central portions of each thereof are at the same level. Tubular guides 22 and 23 are also provided with longitudinally-extended slots 24 and are open-ended in the same manner as guides 18 and 19.

I provide a pair of generally U-shaped material-supporting members 25 and 26, each com-

prising a longitudinally-extended supporting bar 27 and angularly-projecting legs 28 and 29. Legs 28 and 29 are curved on an arc of substantially the same radius as the arcs of tubular guides 18, 19, 22, and 23. As shown, legs 28 and 29 of supporting member 25 are adapted to be slidably received in guides 18 and 22 respectively, whereas legs 28 and 29 of supporting member 26 are adapted to be similarly received in guides 19 and 23 respectively. Each of the legs 28 and 29 is provided with a headed stop pin 30 extending radially outwardly through a cooperating slot 20 or 24, whereby to limit sliding movements of legs 28 and 29 in their respective guides. Supporting bars 27 are each provided with an angular portion 31 which extends substantially parallel to the tapered portion of ironing board 1. At the point of joinder between the angular portion 31 and leg 28 of each supporting member 25 and 26 is an offset portion 32 (see particularly Fig. 4), which is of sufficient height to cause legs 28 to be disposed at a common level with legs 29. Supporting members 25 and 26 are movable from an inoperative position, wherein the supporting bars 27 lie closely adjacent the longitudinal side edges of the ironing board 1, as illustrated in Fig. 3, to an extended operative position shown in Figs. 1, 2, 4, and 5. The curvature of legs 28 and 29 and cooperating tubular guides 18, 19, 22, and 23 cause supporting bars 27 to move outwardly and upwardly in an arcuate path. When supporting members 25 and 26 are in their fully extended positions of Figs. 2 and 4, it will be seen that supporting bars 27 thereof automatically assume positions wherein they are level with the top side of ironing board 1. The weight of such each supporting bar 27 is sufficient to cause a slight binding action between the legs 28 and 29 thereof and their respective tubular guides to prevent accidental sliding movements of the legs within the tubular guides so that supporting bars 27 will remain in their adjusted positions regardless of the weight of material supported thereby. The stop pins 30 working in their respective slots 20 and 24 prevent the legs of supporting members 25 and 26 from being accidentally moved entirely out of engagement with their respective tubular guides.

Supporting members 25 and 26 may be used singularly or together when ironing material having considerable length, such as sheets, curtains, table cloths, or the like, whereby to prevent either the ironed or unironed portions of the material from coming into contact with the floor and being soiled. The unironed portion may be draped over one of the supporting bars 27 and, as the sheet is progressively ironed, the ironed portion may then be draped over the opposite supporting bar 27. By this means, not only is the material prevented from contact with the floor but the ironing operation is effectively accelerated. The bars 27 may also be used for supporting material to be ironed or articles which

50

have been ironed, thus eliminating a substantial amount of bending over by the operator.

My invention has been thoroughly tested and found to be adequate for the accomplishment of the objectives set forth. While I have disclosed a preferred embodiment of my invention, it will be understood that the same is capable of modification within the spirit and scope of the invention as defined in the claims.

10 What I claim is:

1. An ironing board attachment comprising an elongated supporting bar having angularly-disposed legs at its opposite ends, said legs being curved upwardly on a common arc from their free ends, and bracket means adapted to be secured to the under side of an ironing board adjacent the side edge thereof for slidable reception of said arcuate legs whereby said supporting bar may be moved from a normal position adjacent the side edge of said board upwardly and outwardly therefrom in an arcuate path to a material-supporting position upwardly and outwardly spaced therefrom.

2. The structure defined in claim 1 in which said bracket means includes a pair of arcuate guide tubes adapted to slidably receive said arcuate legs, said tubes being provided with longitudinally-extended slots, and in further combination with stop pins adjacent the free ends of said legs, said stop pins working in said slots and limiting outward movements of said legs in said tubes.

3. In combination, an ironing board, a pair of brackets secured to the under side of said ironing board in longitudinally-spaced relationship, each of said brackets including a pair of laterally-extended arcuate guide tubes which open outwardly in opposite directions, a pair of elongated supporting bars one adjacent each opposite side edge of said board, each of said supporting bars being provided with arcuate legs which are slidably received one each within one of the guide tubes in opposite brackets whereby said supporting bars may be moved from normal positions closely adjacent the longitudinal side edges of said board outwardly and upwardly in arcuate paths to material-supporting positions.

45 BEATRICE HEDGES.
